EDWARD MASSEY, OF NORTHPORT, NEW YORK, ASSIGNOR TO C. S. HAMMOND AND COMPANY, OF BROOKLYN, NEW YORK, A CORPORATION OF NEW JERSEY

METHOD OF AND APPARATUS FOR SHAPING GORES FOR GEOGRAPHICAL GLOBES
AND THE LIKE

Application filed August 1, 1928. Serial No. 296,849.

My invention relates to a method of and apparatus for shaping paper gores or sectors for geographical globes and the like.

Under the old process of applying the paper sectors or gores having geographical designations thereon to the base globe, it has been usual to wet flat paper gores, apply adhesive, and then, by a laborious and painstaking procedure, to stretch and mould the gores to the globe surface by hand. This process is exceedingly tedious and time-consuming, and unless great care is taken the gores will not match properly and will be wrinkled at the meridian edges.

It has been proposed to pre-shape the paper gores for geographical globes and the like, and it is the principal object of my invention to provide a method of and apparatus for pre-shaping paper gores or sectors before application to geographical globes and the like.

Briefly stated, in carrying out my process in a preferred manner, I may employ a flat, substantially dry paper sector or gore which has been previously printed with appropriate geographical characters. I then very slightly stretch numerous, closely adjacent areas of the paper gore in a longitudinal direction so that the cumulative effect of the 30 closely adjacent stretched portions along the central and adjacent outer meridians will be to cause all meridian lines to be of substantially the same length. The stretching of the gores along meridian lines is preferably greatest at the central meridian of the gore and progressively less along the meridians toward the edges of the gore. The outside edges of the gores, or what may be termed the edge meridians, are preferably 35 left in an unstretched condition, and the gores inwardly from the edges are stretched so that all meridians will be of substantially the same length. The effect of making all meridians of substantially the same length 40 is to produce a substantially spherical shaped sector surface which may be loosely likened to an orange peel sector.

My preferred form of apparatus for making preformed paper gores or sectors includes a die member which may be of sub-

stantially the same shape as the sector to be shaped and provided with a relatively great number of raised portions on the surface, the raised portions being higher along the central meridian line of the die member and being progressively lower along the adjacent meridians toward the edges of the die. The raised portions may be formed by ruling grooves at right angles to the meridian lines and forming the grooves deeper along 55 the central meridian or meridians and shallower toward the edges. It will ordinarily be more convenient to rule the closely adjacent grooves of uniform depth and then carefully grind or otherwise taper off the projections between adjacent grooves toward the edges of the die.

In the drawings which show, for illustrative purposes only, a preferred form of the invention—

Fig. 1 is a fragmentary diagrammatic view of a press which may be utilized in connection with my invention;

Fig. 2 is an enlarged detail and partially diagrammatic view of a die illustrative of 75 one feature of my invention;

Fig. 3 is a much enlarged sectional view taken substantially in the plane of the line 3—3 of Fig. 2;

Fig. 4 is a view similar to Fig. 3 but taken 80 substantially in the plane of the line 4—4 of Fig. 2;

Fig. 5 is an isometric view of a paper sector or gore shaped in accordance with my invention;

Fig. 6 is a sectional view taken substantially in the plane of the line 6—6 of Fig. 5.

In said drawings, 1 indicates a plate or platen of a press having what may be termed a die member 2 thereon. 3 indicates the head or punch portion of a press having a die member 4 thereon for cooperation with the complementary die member 2. One of the die members, and preferably that indicated as 4 in Fig. 1, is preferably shaped in outline like 90 the sector or gore of a geographical globe. This die member may be substantially flat as shown, or if desired may be bowed slightly both along the meridian and equatorial lines.

One of the die members such as 4 is pro-

vided with means for stretching a paper gore 5 along the meridian lines so that all meridians will be of substantially the same length to cause the finished paper gore to be 10 of substantially the shape of the sector of the spherical surface to which it is to be applied. In the specific form shown, I form numerous, closely adjacent grooves 6 along lines at right angles to the meridian lines, and in order to have the lands or raised portions between the closely adjacent grooves lower at the edges 15 than at the central portion, I preferably grind off or otherwise remove the lands toward the edges as indicated at 7. This removal of the lands is preferably substantially 20 progressively uniform from the central meridian toward the edges so that along the edges of the die member 4 the lands will practically disappear. It should be understood 25 that the lands between adjacent grooves should be rather close together and of but slight depth in order to avoid undue concentrated stretching of the paper gores.

Now, when the die member 4 which is preferably made of metal has been provided with the grooves above described it is mounted on a press preferably as the movable member thereof, and a coacting die member 2 having a preferably smooth surface is mounted upon 30 the complementary member of the press. The die member 2 may be made of heavy cardboard, bakelite, or other substance into which the ridges on the die 4 may slightly force the paper of the gores, and which will permit 35 the shaping of the paper gores to be effectively accomplished. It would be possible to form the complementary die member 2 with grooves and lands complementary to those of the die member 4, but due to the difficulty of 40 always registering the die members in commercial presses, I believe that only one grooved die such as 4 is preferable. With such a single formed die, I have secured highly satisfactory results. A flat paper gore 45 is placed upon one of the die members, and the two then brought together with the requisite force. The grain of the paper preferably extends crosswise of the gore; that is to say, along lines substantially at right 50 angles to the meridian lines so that the lands on the die member 4 may separate to a very slight extent the fibers of the paper gore without injuriously stretching the fibers so as to materially weaken the finished gore. Due to 55 the close proximity of the lands on the die 4, the paper gore is very slightly stretched at a great number of closely adjacent sections which preferably extend substantially from end to end of the gore, and as soon as the dies 2 and 4 are separated, the paper gore 60 will curl longitudinally substantially into a sector of a sphere or into what may be termed orange peel formation substantially as shown in Fig. 5. With a properly made die, all of the meridians of the gore will be of substan-

tially the same length. The gores may then be very readily placed upon a base globe of the proper curvature to which they will substantially conform and may be secured there- 70 to by an adhesive.

It will be apparent to those skilled in the art that by the simple process of pre-shaping the gores in accordance with my invention, a great deal of time will be saved in the application of the paper gores to a base globe. It will furthermore be seen that by the slight lengthening of the inner meridians by means of numerous, closely adjacent stretched portions, there will be little or no distortion of the geographical designations on the face of the gores. It will not ordinarily be necessary, but if it be found desirable, the printing of the geographical designations on the gores may be distorted to the necessary extent while printing and this distortion rectified during 80 the preforming of the gores. 85

While the invention has been described in considerable detail and one apparatus for carrying out the process has been disclosed in considerable detail, I do not wish to be strictly limited to the exact disclosure herein for changes may be made within the scope of the invention as defined in the appended claims. 90

I claim:

1. The method of pre-shaping a paper sector or gore for a geographical globe or the like, which consists in stretching the central meridian line of the sector at numerous, closely adjacent points while the gore is disposed substantially flat so that the edge meridians and the central meridian will be of substantially the same length. 95

2. The method of pre-shaping a paper sector or gore for a geographical globe or the like, which consists in stretching the paper gore along the central meridian line at numerous, closely adjacent but spaced portions while the gore is disposed substantially flat until the central meridian of the gore is of substantially the same length as the edge meridians thereof. 105

3. The method of pre-shaping a paper sector or gore for a geographical globe or the like, which consists in stretching the paper gore along inner meridian lines at numerous, closely adjacent portions while the gore is disposed substantially flat until the inner meridian lines of the gore are of substantially the same length as the edge meridians thereof. 115

4. The method of forming pre-shaped gores or sectors for a geographical globe or the like, which comprises forming a die member with numerous, closely adjacent projections on the face thereof with the projections higher along the inner meridian lines than along the edge meridians, and then pressing a flat paper gore with the die so as to cause the numerous projections to stretch the inner meridian lines and cause the latter to be of sub- 120

stantially the same length as the edge meridian lines.

5. The method of forming pre-shaped paper gores for geographical globes and the like, which comprises forming numerous, small, closely adjacent projections on a die member with the height of the projections decreasing gradually from the central zone thereof toward the edges, and then impressing the die on a flat paper gore so as to cause the projections to stretch the paper gore and cause the inner meridian lines to be of substantially the same length and of substantially the same length as the edge meridian lines.

10 6. Apparatus for pre-shaping the paper sectors or gores for geographical globes and the like, which includes a die member having numerous, closely adjacent projections on one 20 of the gore engaging surfaces thereof, the height of said projections being progressively greater along the inner meridian lines than along the outer meridian lines of the die.

7. Apparatus for pre-shaping paper gores 25 or sectors for geographical globes and the like, which includes a die member having numerous transverse lands upon one of the gore engaging surfaces thereof, the height of said lands being progressively less toward the 30 edges than at the center.

8. The method of pre-shaping a gore for a geographical globe or the like, which consists in forming a sector shaped flat strip of paper having oppositely curved edges to form 35 the edge meridian lines of a finished gore, then applying pressure to that part of the sector between said meridian lines to form a large number of fine, closely arranged indentations on one surface of the sector to displace 40 the fibers and to stretch said inner part lengthwise, thereby giving to the finished gore an orange peel formation.

EDWARD MASSEY.
